UNITED STATES PATENT OFFICE

112,814

DESIGN FOR A RUG-MAKING LOOM

Carl Lovgren, Wilmette, Walter J. Burgess, Park Ridge, and Vera P. Guild, Chicago, Ill., assignors to T. Buettner & Co., Inc., Chicago, Ill., a corporation of Illinois

Application November 15, 1938, Serial No. 81,122

Term of patent 14 years

To all whom it may concern:

Be it known that we, Carl Lovgren, Walter J. Burgess, and Vera P. Guild, all citizens of the United States, residing at Wilmette, Park Ridge, and Chicago, respectively, all in the county of Cook and State of Illinois, have invented a new, original, and ornamental Design for a Rug-Making Loom, of which the following is a specification, reference being had to the accompanying drawing, forming part thereof wherein—

Fig. 2 is a top plan view; and
Fig. 3 is an end elevation of a rug-making loom showing our new design.

We claim:

The ornamental design for a rug-making loom, as shown.

CARL LOVGREN.
WALTER J. BURGESS.
VERA P. GUILD.
